DORY WITH REAR ENGINE WELL

John D. Palmer, 7702 Speedway, Everett, Wash. 98203

Filed Dec. 23, 1974, Ser. No. 535,171

Term of patent 14 years

Int. Cl. D12—06

U.S. Cl. D12—62

FIG. 1

FIG. 2

FIG. 3

FIG. 4

FIG. 5

FIG. 6

FIG. 1 is a perspective view of a dory with rear engine well embodying my invention.

FIG. 2 is a top plan view thereof;

FIG. 3 is a side elevational view thereof;

FIG. 4 is a bottom plan view thereof;

FIG. 5 is a front elevational view thereof;

FIG. 6 is a rear elevational view thereof.

I claim:

The ornamental design for a dory with rear engine well, as shown and described.
